(57) CLAIM

The ornamental design for a tissue file, as shown and described.

DESCRIPTION

FIG. 1 is a top, front, right perspective view of a tissue file, showing my new design;

FIG. 2 is a bottom, rear, left perspective view thereof;

FIG. 3 is a front elevation view thereof;

FIG. 4 is a rear elevation view thereof;

FIG. 5 is a right side view thereof, with the left side view being identical thereto;

FIG. 6 is a top plan view thereof;

FIG. 7 is a bottom plan view thereof;

FIG. 8 is an enlarged view of part of the tissue file shown in FIG. 5; and,

FIG. 9 is an enlarged view of part of the tissue file shown in FIG. 6.

1 Claim, 6 Drawing Sheets

FIG. 1

FIG. 2

FIG. 3

FIG. 4

FIG. 5

FIG. 8

FIG. 9
